SAFETY RAZOR

Roman E. Chojnacki, Milwaukee, Wis.

Application May 20, 1932, Serial No. 612,423

3 Claims. (Cl. 30—12)

This invention appertains to cutlery and more particularly to a novel razor of the safety type.

Considerable difficulty is experienced in the use of safety razors in that the blades tend to collect dirt and unless blades are thoroughly dried the same will rust and decrease the sharpness of the cutting edge.

It is, therefore, one of the primary objects of my invention to provide novel means for maintaining the blade at all times in a clean and sanitary condition and in a dry state, without the necessity of removing the blade from the holder after the razor is used.

Another prime object of my invention is the provision of novel means for mounting the blade within the holder, whereby the blade can be moved into and out of a projecting operative position by manipulation of the handle, means being provided for automatically wiping the blade during the movement thereof into and out of its operative position.

A further object of my invention is the provision of a safety razor embodying a holder having facing resilient wiping pads between which the blade is adapted to be mounted for sliding movement with means controlled from the handle for sliding the blade in the holder between the pads, the pads acting to wipe the blade when the blade is moved into a retracted position in the holder.

A further object of my invention is the provision of use of elastic or resilient pads for gripping contact with the opposite faces of the blade, the pads forming a substantial air and water-tight seal with the blade, whereby only the cutting edge of the blade will be exposed to the action of the water, when the blade is in its projected position, the cutting edge of the blade being movable between the pads and thoroughly wiped after the razor has been used and when the blade is moved to its retracted inoperative position.

A further object of my invention is the provision of novel means for sliding the blade in the holder between the resilient or flexible pads, said means embodying a sliding rack bar for detachably engaging the blade and an operating handle connected with the rack bar.

With these and other objects in view, the invention consists in the novel construction, arrangement and formation of parts, as will be hereinafter more specifically described, claimed and illustrated in the accompanying drawing, in which drawing:

55 Figure 1 is a side elevation of a razor constructed in accordance with my invention, the holder portion of the razor being shown in transverse section, the section being taken substantially on the line 1—1 of Figure 6 looking in the direction of the arrows.

Figure 2 is a view similar to Figure 1 showing the blade in its retracted inoperative position.

Figure 3 is a transverse section through the holder taken on the line 3—3 of Figure 6 showing the blade in its retracted position.

Figure 4 is a top plan view of the razor with the handle partially broken away.

Figure 5 is a fragmentary section illustrating the guide for the lift or rack bar of the razor blade.

Figure 6 is a front elevation of my improved razor.

Referring to the drawing in detail, wherein similar reference characters designate the corresponding parts throughout the several views, the letter A generally indicates my improved razor which comprises the holder 10 and the movable handle 35.

The holder 10 comprises a back or guard plate 11 constructed from any preferred metal suitably plated or otherwise treated to enhance the appearance thereof. The extreme lower edge of the back plate 11 is offset forwardly as at 12 and then bent rearwardly as at 13 to form the guard. The guard 13 and the offset 12 can be provided with slits, if desired, to form a substantial guard plate. The plate 11 at its transverse center and above the offset portion 12 is provided with a rearwardly directed struck-out guide portion 14 which forms a channel for slidably receiving the lift or rack bar 15 for the razor blade 16.

The razor blade 16 is formed in the ordinary manner from thin tempered steel and the same is provided adjacent to its transverse center with an opening 17 for receiving the forwardly projecting foot 18 formed on the inner end of the lift or rack bar 15. Hingedly connected to the upper edge of the back plate 11 is a swinging front plate 19. As shown, the upper edge of the front plate 19 curves rearwardly as at 20 and is provided with circular hinge barrels 21 for reception in the slots 22 formed on the back plate 11. The lower edge of the front plate 19 curves inwardly as at 23 toward the back plate but terminates in slightly spaced relation to the offset portion 12 of said back plate. The side edges of the front plate are provided with rearwardly directed side walls or flanges 24 which carry suitable resilient clips 25 for engaging over the back plate. This detachably locks the front plate with the back plate. As shown, the guard plate 13 of the back plate is provided adjacent to its opposite ends with forwardly projecting guard fingers 26 which receive the lower edge of the blade to limit the outward movement thereof and to prevent injury to the blade by coming in contact with foreign objects.

In accordance with my invention I provide facing pads 27 and 28 formed of resilient com-

pressible material such as rubber and these pads 27 and 28 are secured respectively to the inner faces of the front plate 19 and the back plate 11. As shown, these pads 27 and 28 cover substantially the entire inner face of the front and rear plates and extend from one end of the same to the other and engage the top edges of the plates. The lower edges of the pads terminate short of the lower edges of the plates 11 and 19, so that the cutting blade 16 can extend below the pads when the blade is in its shaving position. These pads can be secured in place in any preferred manner, such as by the use of small rivets 29. Thus, one pad is carried by the plate 19 and the other pad 15 is carried by the plate 11. When the plate 19 is swung over the plate 11 to its closed position, the meeting faces of the pads abut so as to compress the pads, for a purpose which will be hereinafter more fully set forth.

20. The shaving blade 16 is received between the pads 27 and 28 and the pads are provided with narrow registering slots 30 through which extend the foot 18 of the lift bar 15. The provision of the slots 30 allows the engagement of the foot 18 with the opening in the razor blade.

The upper edge of the back plate 11 is provided with a rearwardly inclined supporting arm or bracket 31 having formed on its upper edge the knob 32. This arm 31 is of a resilient nature 30 and acts as means for confining the handle 35 in a pre-determined position, as will be later described.

The handle 35 can be formed in any desired manner, but I prefer to make the same of tubular construction to provide a hand grip 36. The forward end of the hand grip 36 is provided with a forwardly projecting arm 37, which is in turn provided with the offset forwardly extending leg 38. The front end of the leg is provided with a hinge barrel 39 for engaging the upper end of the lift bar 15. The leg 38 is provided with an opening 40 through which the catch or resilient arm 31 is adapted to project when the handle is in one of its positions. As clearly shown in Figure 1 of the drawing, the knob 32 of the arm or catch 31 is adapted to snap over the outer face of the leg and hold the handle against movement. If desired, the hand grip portion 36 of the handle can be provided with out-struck annular beads 41, 50 so as to insure the forming of a proper grip on the handle.

By referring to Figure 5 of the drawing, it will be noted that the lift bar is slidably mounted within the struck-out guide 14 and that the lift bar has its side edges provided with slots 42 which receive the side walls of the out-struck guide 14.

By this construction all lateral shifting movement of the lift bar is prevented but the same is permitted a free sliding movement toward and away from the guard plate 13.

In the use of my improved razor, the blade 16 can be placed in position by raising the front plate 19 and the blade can be laid on the pad 28 with the foot 18 extending through the opening 17. The front plate 19 can now be moved to its closed position and retained in this position by means of the resilient catches 25.

When it is desired to shave with the razor, the handle is swung downwardly which will move the lift bar 15 toward the guard 13. This movement will carry the blade 16 to its operative shaving position and the handle will be held against accidental swinging movement by the knob 32 of the resilient arm 31.

The razor can now be handled in the ordinary

manner for shaving and after the shaving operation has been accomplished, the cutting edge of the blade and the guard 13 can be washed by holding the same under the faucet. The knob 32 can now be depressed and the handle 35 is swung outwardly and the lift bar 15 is pulled outwardly. This will carry the blade 16 between the pads 27 and 28 and move the cutting edge of the blade inward between the pads. The pads will exert a wiping action on the blade removing all foreign matter therefrom and at the same time leaving the same in a dry condition. In view of the tight contact between the pads, the blade, when the same is in its retracted position, will be confined substantially in an air tight condition between the pads.

By my improved construction of razor only the cutting edge of the blade will be exposed, when the razor is in use and thus, the major portion of the blade is protected from the water.

Obviously, the necessity of taking the razor apart for cleaning the blade after each shave is eliminated and the blade is thoroughly wiped merely by pulling outwardly on the lift bar. This insures proper care of the blade and the consequent long life thereto.

Likewise, the dispensing of the wiping of the razor blade on hand towels is eliminated and consequently, the likelihood of cutting the towels is eliminated.

Changes in details may be made without departing from the spirit or the scope of this invention, but what I claim as new is:

1. A safety razor comprising a pair of clamping plates, means for uniting the plates for clamping a blade therebetween, a pair of facing compressible pads carried by the inner faces of the plates, a blade received between the pads having its cutting edge movable exteriorly of the pads when the blade is in one position for shaving purposes, the pads entirely encasing the blade, when the blade is in another one of its positions, a manipulating handle, and means for sliding the blade between the pads from the handle.

2. A safety razor comprising a back plate having a guard at one longitudinal edge, a front plate hingedly connected to the other longitudinal edge of the back plate, means releasably connecting the plates together adjacent to their free edges, a cutting blade, a compressible pad secured to the inner face of each plate, the pads being of sufficient size to completely enclose the blade when the same is in one of its positions, the pads terminating short of the free edges of the plates, and means for sliding the blade between the pads.

3. A safety razor comprising a back plate having a rearwardly struck-out guide channel formed therein, one longitudinal edge of the back plate being provided with a guard, a front plate hingedly connected with the other longitudinal edge of the back plate, means releasably connecting the front plate adjacent to its free edge with the back plate, a pair of compressible pads secured to the inner faces of the front and back plates, a blade slidably mounted between the pads having an opening therein, a lift bar slidably mounted in the channel having a forwardly directed foot detachably received in the opening, a manipulating handle connecting with the upper end of the lift bar, and means releasably connecting the handle to one of the plates.

ROMAN E. CHOJNACKI. 150
